United States Patent Office

Des. 211,848
Patented Aug. 6, 1968

211,848

BASEBALL GLOVE OR SIMILAR ARTICLE

Joseph N. Khazzam, Baldwin, N.Y. (% Regent Sports Co., 131 Varick St., New York, N.Y. 10013)

Filed Aug. 9, 1967, Ser. No. 8,168

Term of patent 14 years

(Cl. D2—361)

FIG. 1 is a front perspective view of a baseball glove, showing my new design; and

FIG. 2 is a rear perspective view thereof.

The essential features of my design reside in the full line disclosure.

I claim:

The ornamental design for a baseball glove or similar article, as shown and described.
